PAVEMENT STRUCTURE

Edward H. Holmes, McKees Rocks, Pa., assignor
to Fort Pitt Malleable Iron Company, McKees
Rocks, Pa., a corporation of Pennsylvania

Application December 26, 1940, Serial No. 371,663

3 Claims. (Cl. 94—8)

My invention relates to the paving or floor art and more particularly to the use of grid-like or grating inserts in paving or floors, whose main body portion consists of ordinary concrete mixtures, bituminous concrete and other materials put into place while in a plastic condition. The grids are also capable of use in flooring, without being inset into other paving material.

One object of my invention is to provide grid inserts of such nature that they will not only serve to prevent skidding on the pavement or floor, but which will also serve as reinforcement to bind the main pavement structure against cracking and spawling, as well as to present hard wearing areas at the pavement surface.

Another object of my invention is to provide reinforcing grids of such form that they can conveniently be installed and embedded in the concrete or other paving material, or placed as flooring, and wherein the various grid elements are interlocked with one another against relative displacement in any direction.

Still another object of my invention is to provide an improved manner of installing reinforcing grids in pavements formed of plastic material.

Briefly stated, my invention comprises the use of metal grids or gratings which usually will be inlaid in the top surface of a pavement, with the upper surfaces of the metal members exposed and with the various metal members interlocked with one another.

Some of the forms which my invention may take are shown in the accompanying drawings wherein Figure 1 is a plan view of one of the grid elements entering into a completed structure; Fig. 2 is an end view thereof taken on the line II—II of Fig. 1; Fig. 3 is a view taken on the line III—III of Fig. 1; Fig. 4 is a view taken on the line IV—IV of Fig. 1, but also indicating the concrete in which the grid is installed; Fig. 5 is a sectional view on a reduced scale of an assembly of the grid elements; Fig. 6 is a plan view thereof; Fig. 7 is a schematic view on a larger scale, showing the manner in which the grid elements of Figs. 5 and 6 may be brought into interlocking engagement with one another at the place of installation; Fig. 8 is a plan view showing a modification of the form of grid shown in Fig. 1, and Fig. 9 is a view taken on the line IX—IX of Fig. 8.

Referring first to Figs. 1 to 7, I show metallic grid elements which may suitably be of malleable iron castings. The grid elements are shown as what may be termed full-size elements 10 and

15 half-size elements 11. The half-size elements are provided in order that the full-size elements 10 in each row may be placed in offset or staggered relation with respect to the elements 10 of the adjacent rows, the half-width elements 11 serving to fill in the half-width spaces that would otherwise be left in certain of the rows, as shown in Fig. 6. The mat-like structure formed by interlocking of the grid elements may be placed in a floor or roadway so that the rows of grid elements which are shown in Fig. 6 as extending lengthwise of the drawing usually will be laid crosswise of the roadway or pavement in which the grids are placed.

20 Each grid comprises bar-like portions 12 that extend lengthwise of the grid and cross bars 13 that are preferably cast or otherwise formed integrally with the bars 12. As shown in Fig. 1, each full-size grid has eight bar-like portions 12. In the case of a half-width grid, there are only four of these portions 12. Each grid also has at its edges short bar-like projections 14 whose outer ends will abut against the outer ends of similarly-formed projections on adjacent grids when the grids are assembled as in Fig. 6.

25 Each grid 10 has four hooks 15 at one end, with an underlying lip or lug 16 beneath each hook, as shown more clearly in Fig. 3. The half-width grids 11 have only two of these hooks and lips. At its other end, each grid has cross bars 17 of reduced depth so that when the hooks 15 of an adjacent grid is engaged with the bars 11, the top surfaces of such hooks will be approximately flush with the top surfaces of the bars 12 and 13.

30 When the grid structure is to be placed in soft concrete, the concrete paving is laid and, while it is still in a plastic condition, a row of grid elements will be installed one-by-one, in interlocked relation. To this end, a row of grids is laid preferably crosswise of the pavement, whereupon grids of the next row are placed in position. By tilting the grids of each row as indicated in Fig. 7, the lugs 16 may be caused to pass beneath the end bars 17, so that when the grids of a succeeding row are brought into horizontal alignment with the grids of a preceding row, the grids will be interlocked with one another, as shown in Fig. 5.

35 Each grid 10 has interlocked engagement with two grids of the adjacent rows and each half-width grid 11 will have interlocking engagement with the full-width grids 10 of the adjacent rows, as shown in Fig. 6, so that the grids are all interlocked together against displacement in horizontal directions, the hooks 15 and lugs

16 serving to lock the grids against relative displacement also in vertical directions.

After a desired number of grids have been assembled to mat form, as shown in Fig. 6, they can be depressed into the concrete—preferably to a plane at which the surface of the concrete is approximately flush with the tops of the grids. As fast as new concrete is laid and struck off, additional rows of grids will be applied to the preceding rows. The hook connections of the grids have sufficient play to permit the grids to follow a slightly curved contour such as in crowned roadways, bridges, tunnels and even curves of long radius on highways. Such small lumps or masses of concrete as extend too high above the ribs can be struck off by a straight-edge or the like. On certain of the bars 12 I provide foot-like extensions 19 that will become embedded in the concrete and serve as an anchoring means.

The grids can also be utilized in connection with pavements of bituminous material, in which case they will be placed on a suitable surface such as some sort of concrete, and thereafter the asphalt or other bituminous material spread upon and rolled into the grids.

As above stated, the grids serve not only as anti-skid elements, but as reinforcement for the paving material, and also as a wear-resisting surface. Although the concrete may initially be flush with the grids, it will soon wear down slightly, so that tires of vehicles or the feet of pedestrians can have anti-slipping engagement with the bars 12 and 13, even in the case of factory floors where grease may occasionally be present on the floor. The grids have the further utility in connection with asphalt paving, in that they limit the extent to which the asphalt tends to become displaced under traffic when the temperature is warm, thus preventing the forming of the ridges or depressions that commonly occur in asphalt surfaces of wide area, since the bars 12 and 13 are sufficiently close together to prevent substantial displacement of the asphalt in this manner. By way of example, the bars 12 may be only from one or two inches apart, while the bars 13 may be only three or four inches apart.

In Figs. 8 and 9 I show a grid structure 20 which may be made in full-width and half-width pieces as are the elements 10 and 11. In this arrangement, there is a top plate 21 which almost entirely covers the concrete and which

has depending ribs 22 and 23 that extend lengthwise and crosswise of the grid plate, the grids being also provided with hooks 24 and lugs 25 that correspond to the hooks and lugs 15—16 and also provided with hook-engaging bars 26. In this arrangement the plate 21 has upstanding bosses distributed over its top surface, as indicated at 27, that constitute the anti-slipping elements. Holes 28 are provided to permit escape of air from beneath the plate 21 when the grids are being placed in the concrete. It will be understood that when desired, an anti-slipping surface can be provided by making cut-outs through the plate 21, at the points 27, instead of forming the protuberances.

I claim as my invention:

1. A pavement structure comprising a body of concrete or the like which has inset into its upper surface grid-like members each of which has a hook-engaging bar of reduced depth at one edge and a hook at the opposite edge, with a retaining lug beneath the hook, the hook on each grid partially embracing the bar of an adjacent grid and the retaining lug at the hook underlying the bar, whereby the grids are held against relative displacement.

2. A pavement structure comprising a body of concrete or the like which has inset into its upper surface grid-like members each of which has longitudinal bars connected by cross bars, to form a grating, hooks formed on the cross bars at one end of each grid member, and the cross bars at the other end being of reduced depth, the hooks on each grid member having hooked engagement with the reduced bars of an adjacent grid.

3. A grating structure for use in a flooring, comprising grid-like elements each having hooks at one edge and retaining lugs in vertically spaced relation to the open sides of the hooks, and also having hook-engaging bars at its opposite edge, of reduced depth relative to the over-all thickness of the grid and each of less depth than the space between the adjacent hook and retaining lug, the hooks of each grid being engageable behind the bars of an adjacent grid when the grid is tilted to a plane generally perpendicular to the plane of the adjacent grid, and the retaining lugs, the bar and hooks at each connection being in superposed relation when the connected grids are brought to a common plane.

EDWARD H. HOLMES.
